UNITED STATES PATENT OFFICE.

WILLIAM BOWN AND JOSEPH HENRY HUGHES, OF BIRMINGHAM, ENGLAND.

DESIGN FOR A FORK AND CROWN FOR VELOCIPEDES.

SPECIFICATION forming part of Design No. 25,974, dated August 25, 1896.

Application filed July 25, 1896. Serial No. 600,566. Term of patent 14 years.

To all whom it may concern:

Be it known that we, WILLIAM BOWN and JOSEPH HENRY HUGHES, subjects of the Queen of Great Britain, residing at Birmingham, in the county of Warwick, England, have invented and produced a new and original Design in Forks and Crowns for Velocipedes, reference being had to the accompanying drawing, forming a part hereof.

10 In the accompanying drawing the figure is a perspective view of our design.

The leading feature of our design consists in a diamond-shaped tubular portion arranged in a horizontal plane and having bosses or 15 projections thereon at or near its end portions and at or near its central portion.

A is the diamond-shaped portion, arranged in a horizontal plane; B B, the shoulder pro-

jections at or near each end; C C, the depending portions therefrom; D, a shoulder 20 projection at or near the central portion, and E the projection at or near the central portion extending upwardly therefrom, the whole presenting to the eye a harmonious and ornate figure, as shown in the accompanying drawing. 25

We claim—

The design for a fork and crown for velocipedes, substantially as herein shown and described.

WILLIAM BOWN.

JOSEPH HENRY HUGHES.
